CHRISTOPHER S. SPOFFORD AND FREDERICK W. JONAS, OF STURGIS, MICHIGAN,
ASSIGNORS TO STURGIS STEEL GO-CART CO., OF STURGIS, MICHIGAN.

WHEEL-ATTACHING DEVICE.

1,202,448.

Specification of Letters Patent. Patented Oct. 24, 1916.

Application filed January 28, 1916. Serial No. 74,907.

To all whom it may concern:

Be it known that we, CHRISTOPHER S. SPOFFORD and FREDERICK W. JONAS, citizens of the United States, residing at Sturgis, county of St. Joseph, State of Michigan, have invented certain new and useful Improvements in Wheel-Attaching Devices, of which the following is a specification.

This invention relates to improvements in wheel attaching devices.

Our improved wheel attaching device is especially designed by us for use on carriages, such as children's carriages, although it may be readily adapted for use in other relations.

The main objects of our invention are: First, to provide an improved wheel attaching device which is effective and at the same time simple in structure and easily manipulated to secure or release the wheel. Second, to provide an improved wheel attaching device which is compact and does not detract from the appearance of the carriage and which also serves as a thrust collar for the wheel.

Further objects, and objects relating to structural details, will definitely appear from the detailed description to follow.

We accomplish the objects of our invention by the devices and means described in the following specification. The invention is clearly defined and pointed out in the claims.

A structure which is a preferred embodiment of our invention is clearly illustrated in the accompanying drawing, forming a part of this specification, in which:

Figure I is a detail inside view of a structure embodying the features of our invention, the axle being shown in section on a line corresponding to line 1—1 of Fig. III. Fig. II is a front perspective view of our improved wheel attaching device removed from the axle. Fig. III is a detail view, partially in section, on a line corresponding to line 3—3 of Figs. I and IV. Fig. IV is a detail section on a line corresponding to line 4—4 of Fig. III. Fig. V is an enlarged detail section corresponding to line 5—5 of Fig. I, showing details of the wheel attaching means.

In the drawing, similar reference characters refer to similar parts throughout the

several views, and the sectional views are taken looking in the direction of the little arrows at the ends of the section lines.

Referring to the drawing, the axle 1 is provided with a spindle 2. The hub 3 of the wheel is provided with a flange 4 at its inner end. A collar 5 is sleeved upon the spindle of the axle and is provided with an integral rearwardly projecting attaching arm 6 having flanges 7 at its edges embracing the axle, the arm being secured by means of the rivet 8. The collar 5 is, in practice, preferably a sheet metal stamping, the attaching arm being formed integrally therewith.

At one side the collar is provided with an integral projecting pivot ear 9, the ear being forwardly offset so that the flange engaging latch 10 is supported in a spaced relation to the collar to receive the flange of the hub between. The latch member 10 is formed of wire and is provided with an eye 11 for the pivot 12. The swinging end of the latch member is provided with a loop 13, the end of the loop 14 being in sliding engagement with the rear side of the collar and constituting a spring for retaining the latch member in its adjusted position. The collar is provided with a forwardly projecting flange 15 opposite its pivot ear and the latch is held in frictional engagement with the edge of this flange by means of its spring loop 13.

The flange is provided with stops 16 which limit the movement of the latch. The collar is preferably provided with a lug-like keeper 17 which is struck up from the latch so that the end of the spring loop snaps over this lug when the latch is in its flange engaging position and is thereby effectively retained in that position.

To release the wheel it is only necessary to swing the latch member to the position shown in Fig. II and it is quickly engaged with the hub flange by swinging it to the position shown in Figs. I, III, IV and V.

With the parts thus arranged, our improved attaching device serves as a thrust collar as well as a means for retaining the wheel. It is very simple and economical to produce and is easy and convenient to manipulate and, further, is neat and attractive in appearance.

Having thus described our invention, what we claim as new and desire to secure by Letters Patent, is:

1. In a structure of the class described, 5 the combination with an axle and a wheel hub provided with a flange at its inner end, of a collar sleeved upon said axle and having an integral rearwardly projecting attaching arm secured to the axle and having an 10 integral offset pivot ear and a flange disposed oppositely to said pivot ear and provided with spaced stops, and a hub flange engaging latch member pivotally mounted on said pivot ear to swing in sliding engagement with said flange between said stops and having a loop at its swinging end disposed with the end of the loop engaging the rear side of the collar and constituting a latch retaining spring, said collar having 15 a keeper lug struck therefrom and over which the retaining spring engages when the latch member is swung to its hub flange engaging position.
2. In a structure of the class described, 20 25 the combination with an axle and a wheel hub provided with a flange at its inner end, of a collar sleeved upon and secured to said axle and having an integral offset pivot ear and a flange disposed oppositely to said pivot ear and provided with spaced stops, 30 a hub flange engaging latch member pivotally mounted on said pivot ear to swing in sliding engagement with said flange between said stops and having a loop at its 35 swinging end disposed with the end of the loop engaging the rear side of the collar and constituting a latch retaining spring and a keeper coacting with said latch when it is in engaging position.
3. In a structure of the class described, 40 45 the combination with an axle and a wheel hub provided with a flange at its inner end, of a collar sleeved upon and secured to said axle and having an integral offset pivot ear and a flange disposed oppositely to said

pivot ear and provided with spaced stops, a hub flange engaging latch member formed of wire pivotally mounted on said pivot ear to swing between said stops, and means for retaining said latch member in its adjusted positions.

4. In a structure of the class described, 50 the combination with an axle and a wheel hub provided with a flange at its inner end, 55 of a collar sleeved upon and secured to said axle and having a pivot ear and spaced stops disposed oppositely to said pivot ear, and a hub flange engaging latch member formed of wire pivotally mounted on said pivot ear to swing between said stops and having a loop at its swinging end disposed with the end of the loop engaging the rear 60 side of the collar and constituting a latch retaining spring, said collar having a keeper lug struck therefrom and over which the retaining spring engages when the latch member is swung to its hub flange engaging position.

5. In a structure of the class described, 65 the combination with an axle and a wheel hub provided with a flange at its inner end, 70 of a collar sleeved upon and secured to said axle and having a pivot ear and spaced stops disposed oppositely to said pivot ear, a hub flange engaging latch member 75 formed of wire pivotally mounted on said pivot ear to swing between said stops and having a loop at its swinging end disposed with the end of the loop engaging the rear side of the collar and constituting a latch retaining spring and a keeper coacting with 80 said latch when it is in engaging position.

In witness whereof we have hereunto set our hands and seals in the presence of two witnesses.
